UNITED STATES PATENT OFFICE.

HERMAN SILVER, OF MINNEAPOLIS, MINNESOTA.

METAL REINFORCED-CONCRETE RAILWAY TIE.

Application filed August 8, 1924, Serial No. 730,879.

To all whom it may concern:

Be it known that I, HERMAN SILVER, a citizen of the United States, residing at Minneapolis, in the county of Hennepin and 5 State of Minnesota, have invented certain new and useful Improvements in Metal Reinforced-Concrete Railway Ties; and I do hereby declare the following to be a full, clear, and exact description of the invention, such as will enable others skilled in 10 the art to which it appertains to make and use the same.

My present invention has for its object to provide a strong, durable, and highly efficient metal reenforced concrete railway tie, and to this end it consists of the novel devices and combinations of devices herein-after described and defined in the claims.

In the accompanying drawings, which illustrate the invention, like characters indicate like parts throughout the several views.

Referring to the drawings:

Fig. 1 is a plan view of my improved railway tie supporting sections of a pair of rails;

Fig. 2 is a longitudinal section taken on the line 2—2 of Fig. 1;

Fig. 3 is a horizontal section taken on the line 3—3 of Fig. 2;

Fig. 4 is a view partly in elevation and partly in transverse vertical section taken on the line 4—4 of Fig. 2, on an enlarged scale;

Fig. 5 is a view partly in elevation and partly in transverse vertical section taken on the line 5—5 of Fig. 2;

Fig. 6 is a detail view principally in section taken on the line 6—6 of Fig. 1, on an enlarged scale; and

Fig. 7 is a detail view partly in plan and partly in section taken on the line 7—7 of Fig. 6.

The numeral 8 indicates the concrete body of a railway tie, and the numeral 9 indicates sections of a pair of rails supported thereon. Embedded in the body 8 is a metal reinforcement comprising a pair of parallel longitudinal tie bars 10, a pair of parallel end tie bars 11, a truss rod 12, and a reinforcement 13 of expanded metal. The tie bars 10 and 11 are in oblique arrangement with the ends of the tie bars 11 resting on the tie bars 10, and which tie bars are thus connected by four upright sleeves

14 which extend through aligned bores 55 therein.

The end bars 11 are turned in respect to the body 8 so that they extend obliquely thereacross and thereby position the sleeves 14 in pairs and with the sleeves of each pair spaced both longitudinally and transversely in respect to the body 8. The truss rod 12 extends below the tie bars 10 and 11 and diagonally between the two outermost sleeves 14, and has in its ends bores through which the respective sleeves project. The tie bars 10 and 11 and truss rod 12 are supported from shoulders 15 on the sleeves 14, and which shoulders are in the form of nuts 60 screwed onto said sleeves from the upper ends thereof and support the ends of the tie bars 10 and 11 and truss rod 12 at a point just slightly above the vertical center of the body 8.

The reinforcement 13 extends above the tie bars 10 and 11 and outward thereof, and parallel to the top and sides of the body 8 and is located substantially midway between said tie bars and the top and side faces of the body 8. This reinforcement 13 is supported on thimbles 16 telescoped onto the sleeves 14 which rest on the end bars 11. Nuts 17 are screwed onto the upper end of the sleeves 14 and clamp the reinforcement 13 thereon and the sleeves onto the tie bars 70 11. On the lower ends of the sleeves 14 are heads 18 recessed to receive the heads of anchor bolts, as will presently appear.

The tie bars 10 and 11 are flat, and the tie bars 10 are twisted between the sleeves 14 90 to increase their hold in the cement and thereby more securely hold said sleeves against longitudinal movement in respect to the body 8. It will be noted that the ends of these tie bars 10 are extended outward of the sleeves 14 and then bent laterally downward at 19 to further increase their hold in the body 8. By reference to Fig. 2 it will be noted that the longitudinal center of the truss rod 12 is only slightly above the bottom face of the body 8 and from this point the end portions thereof diverge upward to the sleeves 14 to which they are attached.

It will be noted that the sleeves 14 extend 105 completely through the body 8 so that their heads 18 are flush with the bottom of said body and the nuts 17 are flush with the top

thereof. The metal reinforcement 13 extends substantially the full length of the body 8. It will be noted that the improved railway tie has no projection whatsoever and hence, ties of this type may be piled one upon the other without danger of breaking or mutilating any of the parts thereof.

The above described metal reinforcement is self-contained with the several parts 10 thereof assembled and held in proper relation to each other before the concrete from which the body 8 is formed is poured therearound to embed said reinforcement therein.

To secure the rails 9 to the body 8 there 15 are provided headed anchor bolts 20 and clips 21. Interposed between the bases of the rails 9 and the top of the body 8 are combined cushion and wearing plates 22 of fibre or other suitable material, and which 20 plates may be easily replaced from time to time or a number thereof used to level up a rail. These plates 22 have bores aligned with the bores in the sleeves 14 and the anchor bolts 20 extend upward through said 25 sleeves and bores in the plate 22 with their heads seated in the recessed heads 18 of said sleeves which hold said bolts from turning. Nuts 23 applied to the bolts 20 clamp the plates 22 on the body 8 and hold said bolts 30 against endwise movement in the sleeves 14.

The clips 21 have longitudinally extended slots 24 through which the upper ends of the anchor bolts 20 project and they also have extended lips 25 arranged to overlap 35 the base flanges of the rails 9 to hold the same on the body 8 with the plates 22 therebetween. The slots 24 permit the clips 21 to be adjusted toward and from the rails 9 and the under surfaces of the lips 25 are 40 beveled to rest directly upon the beveled upper surfaces of the base flanges of said rails. The under sides of the clips 21 are recessed at 26 to receive the nuts 23 and permit said clips to be adjusted over said nuts.

45 Spring washers 27 and nuts 28 applied to the upper ends of the bolts 20 clamp the clips 21 onto the base flanges of the rails 9 with the plates 22 therebetween. The ties are shipped to their destination before the 50 bolts, nuts, washers, clips, and plates are applied thereto and which parts may be shipped in separate containers and then assembled with the body 8 at the time the ties are to be placed on the roadbed to support 55 the rails 9.

What I claim is:

1. A metal reinforced concrete railway tie comprising a concrete body, sleeves extending through said body arranged in longitudinally spaced pairs, a pair of edgewise spaced transverse tie bars and a pair of edgewise spaced longitudinal tie bars connecting the sleeves in endless arrangement, and rail-anchoring means extending into said sleeves.

2. A metal reinforced concrete railway tie comprising a concrete body, sleeves extending through said body arranged in longitudinally spaced pairs, a pair of parallel edgewise spaced transverse tie bars, and a pair 70 of parallel edgewise spaced longitudinal tie bars connecting the sleeves in endless arrangement, and rail-anchoring means extending into said sleeves.

3. The structure defined in claim 2 in further combination with a truss rod connecting one of the sleeves of one of the pairs to one of the sleeves of one of the other pair.

4. A metal reinforced concrete railway tie comprising a concrete body, sleeves in said body arranged in longitudinally spaced pairs, transverse end tie bars connecting the sleeves of each pair, and longitudinal tie bars connecting the sleeves of opposite pairs, the end portions of the transverse and longitudinal tie bars being overlapped and provided with aligned holes through which the sleeves project.

5. A metal reinforced concrete railway tie comprising a concrete body, sleeves in said body arranged in longitudinally spaced pairs, the sleeves of each pair being transversely and longitudinally spaced, parallel transverse end tie bars connecting the sleeves of each pair, parallel longitudinal tie bars connecting opposite sleeves of each pair, the end portions of the transverse and longitudinal tie bars being overlapped and provided with holes through which the sleeves project, and rail-anchoring means including bolts in said sleeves.

6. A metal reinforced concrete railway tie comprising a concrete body, two pairs of sleeves in said body, the sleeves of each pair being longitudinally and transversely spaced, end tie bars connecting the sleeves of each pair, longitudinal twisted tie bars connecting opposite sleeves in the two pairs, and rail-anchoring means including anchor bolts in said sleeves.

7. A metal reinforced concrete railway tie comprising a concrete body, two pairs of sleeves in said body, the sleeves of each pair being longitudinally and transversely spaced, end tie bars connecting the sleeves of each pair, longitudinal tie bars connecting opposite sleeves in the two pairs, a truss rod connecting one of the sleeves of one pair with one of the sleeves of the other pair, and rail-anchoring means including anchor bolts in 115 said sleeves.

8. The structure defined in claim 7 in which the sleeves connected by the truss rod are on opposite sides of the body.

9. The structure defined in claim 7 in further combination with a perforated metal reinforcement in the body extending over the tie bars and outward thereof and substantially parallel with the top and sides of said body.

10. A metal reenforced concrete railway tie comprising a concrete body, sleeves extending through said body, and transverse end tie bars connecting said sleeves in pairs, said sleeves having shoulders from which the tie bars, further combination with a perforated metal reinforcement in the body extending over the tie bars, and spacing thimbles on the sleeves supporting said reinforcement from said end tie bars are supported.

11. The structure defined in claim 10 in

In testimony whereof I affix my signature.

HERMAN SILVER.
